FIXTURE STUD AND HOOK ASSEMBLY

Arthur I. Appleton, Northbrook, Ill.

Application May 22, 1951, Serial No. 227,599

2 Claims. (Cl. 248—340)

The present invention relates generally to electrical fittings and more specifically to a novel assembly for mounting an outlet box or the like on a bar hanger.

In installing bar hangers between the floor joists or studding of buildings under construction, it is customary to fix the box to the bar hanger beforehand. This is usually done by slipping the end of the bar hanger through some sort of suspension fitting which is capable of providing a certain degree of adjustment to orient the box in proper position after the bar hanger is installed in place. Such an arrangement is manifestly unsuitable for use with bar hangers having enlarged ends to facilitate mounting on the joists. It is also undesirable due to the fact that the installer must support and handle the weight of the box and bar hanger combined rather than just the hanger alone.

The general aim of the present invention is to provide a means for attaching a box to a bar hanger so as to overcome the foregoing disadvantages.

More specifically, it is an object of the invention to provide an assembly susceptible of attaching an outlet box or the like to a bar hanger which has already been mounted in place, permitting angular adjustment of the box in a plane parallel to the longitudinal axis of the bar hanger as well as bodily adjustment along such axis.

Another object is to provide an assembly of the character set forth which can be readily hooked over the bar hanger and locked in position to support with perfect safety the box and its associated electrical fixture.

A further object is to provide a fitting of simple, clean-cut construction, being economical to manufacture and exceptionally easy to use.

Other objects and advantages will become apparent as the following detailed description proceeds, taken in connection with the accompanying drawing, wherein:

Figure 1 is a plan view of an installed bar hanger and an outlet box fixed thereto by means of an illustrative fixture stud and hook assembly embodying the present invention.

Fig. 2 is an enlarged fragmentary vertical sectional view through the bar hanger, box and novel assembly of Fig. 1, taken in the plane of the line 2—2.

Fig. 3 is another enlarged fragmentary vertical sectional view through the bar hanger, box and assembly of Fig. 1, but taken in the plane of the line 3—3.

Fig. 4 is a view similar to Fig. 3 but shows the box and the fixture stud and hook assembly in process of being attached to the bar hanger.

Fig. 5 is an enlarged perspective view detailing the stud member of the novel assembly of Fig. 1.

While the invention is susceptible of various modifications and alternative constructions, a preferred embodiment has been shown in the drawing and will be described herein in considerable detail. It should be understood, however, that there is no intention to limit the invention to the specific form disclosed, but on the contrary, the intention is to cover all modifications and alternative constructions falling within the spirit and scope of the invention as expressed in the appended claims.

Referring more particularly to the drawing, the invention is there exemplified in a novel fixture stud and hook assembly 10 which attaches an outlet box 11 to a bar hanger 12. The latter has enlarged ends 14 which happen to be anchored to a pair of laterally spaced floor joists 15. The assembly 10 permits angular adjustment of the box 11 in a plane parallel to the longitudinal axis 80 of the bar hanger 12 as well as bodily adjustment along

such axis. In addition to serving as a means for clamping the box 11 to the hanger 12, the assembly 10 also serves as an anchorage for the supporting stem 16 of an electrical fixture associated with the box 11 (see Fig. 2).

For the purpose of engaging the bar hanger 12, the assembly 10 has a hook 18 of appropriate size to be inserted through knockout opening 19 of the box wall 20. The hook structure includes a relatively heavy, reversely bent finger 21 terminating in a depending stem 22, the latter in this instance having threads 24 for engaging threads 25 within hollow stud 26. The reversely bent hook finger 21 defines a hook aperture 28 for receiving the bar hanger 12 and supporting the assembly 10 and the box 11 in depending relation therefrom.

In order to avoid excessive play in the fit between the hook 18 and the bar hanger 12, and also to avoid any tendency of the hook to slip off the hanger 12, the hook aperture 28 is made only slightly wider than the thickness of the bar hanger and the free end of the hook finger 21 is extended a considerable distance toward the stem 22. Consequently, to permit passage of the hanger 12 laterally into the hook aperture, the stem 22 may be provided with a relief chamfer 29 opposite the free end of the finger 21 while the back wall of the aperture 28 is formed with a transverse relief groove 30 (see Fig. 4). Any weakening of the hook by the groove 30 is offset by means of stiffener rib 31 on the outside of the rear wall.

Provision is made in the assembly 10 for attaching the box 11 to the bar hanger 12 in such a way that the entrance to the hook aperture 28 will become restricted and thereby preclude unhooking of the hook 18 from the bar hanger. This is accomplished by providing the hollow stud 26 with a flange 32 at one end thereof, the flange being of somewhat greater diameter than the knockout opening 19 so as to engage the marginal edge portions of the box wall 20 surrounding the opening 19. In order to center the hook 18 and the stud 26 relative to the knockout opening 19, the flange 32 has an annular centering boss 34 which is adapted to enter the opening 19.

With the structural arrangement just described, it will be noted that the initial step in attaching the box 11 to the bar hanger 12 involves threading the hook stem 22 part way into the hollow stud 26 and thrusting the hook through the knockout opening 19 so that the centering boss registers with the same. The box 11 and the assembly 10 can then be canted as shown in Fig. 4 and hooked over the bar hanger 12. When the upper end of the hook aperture 28 has seated against the top edge of the hanger 12, the hollow stud 26 can be tightened by hand. Due to the pitch of the threads 24, 25, the stud 26 and the box wall 11 will advance toward the bottom edge of the bar hanger 12 as the stud 26 is tightened, eventually accosting such bottom edge and restricting the mouth of the hook aperture 28 so as to preclude disengagement of the hanger 12 therefrom (see Figs. 2 and 3). After the box 11 has been adjusted to the desired angular and longitudinal position relative to the bar hanger 12, the stud 26 may be set tight as by means of a screwdriver inserted into screwdriver slot 35 at the bottom end of the stud.

60 Retrograde movement of the stud 26 after tightening is prevented by means of a series of circumferentially spaced locking teeth 36 stamped or otherwise formed on the upper face of the flange 32. The teeth 36 have relatively sharp biting edges 38 which are adapted to dig into the box wall 11 upon the application of a loosening torque to the stud 26.

I claim as my invention:

65 1. A fixture stud and hook assembly for attaching an outlet box or the like to a bar hanger, said assembly comprising the combination of a hook having a reversely bent finger defining a hook aperture, said hook being insertable through a knockout opening in the wall of the box, a depending threaded stem on said hook, said stem having a relief chamfer opposite the free end of said finger and the hook aperture having a relief groove in its back wall to permit entry of the bar hanger into the hook aperture, a stiffener rib on said hook, a fixture stud threadedly engageable with said stem, a boss on said stud for centering the same and said hook in the knockout opening of the box, a flange on said stud for engaging the marginal portions of the box wall surrounding the knock-

out opening and for forcing the box wall past the relief chamfer so as to restrict the entrance of said hook aperture and preclude withdrawal of the bar hanger therefrom, and means for preventing retrograde movement of said fixture stud after tightening of the same.

2. An assembly for mounting an outlet box or the like in depending relation with a bar hanger, said assembly comprising the combination of a hook having a shank and an aperture therein defined by a reversely bent finger, a relief chamfer on the base portion of said hook opposite a relief chamfer on the shank comprising a cut away portion providing an enlarged entrance to said hook aperture, the relief chamfer being spaced from the hook end to permit lateral entry of the bar hanger into the hook aperture, and means adjustably attached to said hook for fastening the hook to the outlet box and movable along said shank

for obstructing said entrance to preclude disengagement of said hook from said bar hanger.
